Primary Examiner — April Rivas*Assistant Examiner* — Jillian Mazzola(74) *Attorney, Agent, or Firm* — Ricky Lam(57) **CLAIM**

The ornamental design for a set of foldable storage bins, as shown and described.

DESCRIPTION

FIG. 1 is a front perspective view of set of foldable storage bins, showing my new design;

FIG. 2 is a rear perspective view;

FIG. 3 is a front view;

FIG. 4 is a rear view;

FIG. 5 is a left side view;

FIG. 6 is a right side view;

FIG. 7 is a top view; and

FIG. 8 is a bottom view.

FIG. 9 is a usage state view of the set of foldable storage bins; and,

FIG. 10 is an exploded split state view of the set of foldable storage bins.

The broken lines showing storage bins in FIG. 9 depict environmental structure and form no part of the claimed design. The remaining broken lines in the drawings illustrate the portions of the set of foldable storage bins that form no part of the claimed design.
